CLAIM

The ornamental design for a fan blade for a ceiling fan, as shown and described.

DESCRIPTION

FIG. 1 is a front view of the fan blade for a ceiling fan showing my new design;

FIG. 2 is a rear view of the design of FIG. 1;

FIG. 3 is a side view of the design of FIG. 1;

FIG. 4 is another side view of the design of FIG. 1;

FIG. 5 is a view of the top of the design of FIG. 1;

FIG. 6 is a view of the bottom of the design of FIG. 1; and, FIG. 7 is a perspective view of the design of FIG. 1.

The broken line showing of environmental structure in FIGS. 1-4 and 7 is for illustrative purposes only and forms no part of the claimed design. The wood grain pattern fragmentarily shown in FIGS. 1-2 and 7 is understood to extend uniformly throughout the areas represented.
